BLADE FOR A GARDEN HOE

Daniel S. Pontius, 14227 Syracuse St.,
Whittier, Calif. 90604

Filed Sept. 8, 1972, Ser. No. 287,260

Term of patent 14 years

Int. Cl. D8—01

U.S. Cl. D8—11

FIG. 1 is a perspective view of a blade for a garden hoe showing my new design, the broken lines being shown for illustrative purposes only;

FIG. 2 is a side elevational view thereof;

FIG. 3 is an end elevational view thereof; and

FIG. 4 is a bottom plan view thereof.

I claim:

The ornamental design for a blade for a garden hoe, substantially as shown and described.
